(57) **CLAIM**

The ornamental designs for a drive gear for imaging component, as shown and described.

DESCRIPTION

FIG. 1 is a perspective view of a drive gear for imaging component in accordance with a first embodiment of our new design;

FIG. 2 is a front elevational view thereof;

FIG. 3 is a bottom plan view thereof;

FIG. 4 is a top plan view thereof;

FIG. 5 is a right side view thereof;

FIG. 6 is a rear elevational view thereof;

FIG. 7 is a left side view thereof;

FIG. 8 is a perspective view of a drive gear for imaging component in accordance with a second embodiment of our new design;

FIG. 9 is a front elevational view thereof;

FIG. 10 is a bottom plan view thereof;

FIG. 11 is a top plan view thereof;

FIG. 12 is a right side view thereof;

FIG. 13 is a rear elevational view thereof; and,

FIG. 14 is a left side view thereof.

The broken line portion of the figure drawings is included to show portions of the article that form no part of the claimed design.

1 Claim, 14 Drawing Sheets
